UNITED STATES PATENT OFFICE.

MORRIS PARNES, OF NEW YORK, N. Y.

FUEL-SUPPLY SYSTEM.

1,341,515.

Specification of Letters Patent. Patented May 25, 1920.

Application filed November 15, 1919. Serial No. 338,363.

To all whom it may concern:

Be it known that I, MORRIS PARNES, a citizen of Austria, and a resident of the city of New York, borough of Manhattan, in the county and State of New York, have invented a new and Improved Fuel-Supply System, of which the following is a full, clear, and exact description.

The present invention relates to new and useful improvements in fuel systems for internal combustion engines, and it pertains more particularly to that type of fuel systems in which the operation is carried out by means of a partial vacuum.

15 In connection with internal combustion engines, it is sometimes desirable to have the source of fuel supply located at a point remote from the charge-forming device of the engine, and it is not always possible to 20 so position this source of supply as to have a gravity feed of the fuel to said charge-forming device.

In connection with internal combustion engines when their system is arranged as 25 above stated, it is usual to employ an auxiliary tank or receptacle which feeds the charge-forming device by gravity, and to provide automatic means for supplying the auxiliary tank, and it is this type of system 30 to which the present invention more specifically pertains.

It is the primary object of the present invention to supply the auxiliary receptacle with fuel from the main receptacle automatically by the creation of a partial vacuum within the auxiliary receptacle.

It is a further object of the invention to produce this vacuum in the auxiliary receptacle by establishing communication between 40 the auxiliary receptacle and the intake manifold of the motor.

It is a further object of the invention to provide means for automatically controlling the vacuum dependent upon the liquid level 45 in the auxiliary receptacle.

A further object of the invention is to provide a device of this character in which the number of working parts is materially decreased.

50 In the drawings—

Figure 1 is a view partly in section and partly in elevation of the device with the parts in the position which they occupy when the vacuum is operating.

55 Fig. 2 is a similar view with the several

parts in the position which they occupy when the vacuum is cut off.

Referring more specifically to the drawings, the reference character 5 designates a suitable fuel-containing tank or receptacle, 60 which may be located at any point remote from the auxiliary receptacle 6, in so much as it is connected thereto, as shown in the present instance, by means of a pipe or tube 7.

The auxiliary receptacle 6 comprises two chambers 8 and 9, said chambers being formed by interposing a partition 10 between the open ends of two members 11 and 12, said open ends being flanged as at 79 13, and secured together by means of bolts, rivets, or the like 14. The opposite ends of the connecting pipe 7 are secured by screw-threaded collars 16 and 17, to the main supply tank 5, and the upper chamber 8 of 75 the auxiliary receptacle 6, respectively. The upper wall 18 of the chamber 8 of the auxiliary receptacle is provided with an opening 19, with which the connecting pipe or tube 7 communicates.

Rigidly secured to the upper wall 18 of the chamber 8, is a housing 20, the upper face of which is provided with a hollow extension 21, the purpose of which will be hereinafter more fully set forth. The inner 85 or lower end of this housing 20, is provided with a valve seat 22, and leading from said housing at a point preferably on the exterior of the chamber 8, is a pipe or tube 23, which is connected with the manifold 90 of the internal combustion engine with which this device is used, in such a manner that as the engine operates, the effect of the vacuum which is produced affects the interior of the chamber 8 of the auxiliary 95 receptacle 6.

Mounted in the chamber 8 of the auxiliary receptacle and carried by the partition 10, is a vertical tubular extension 25, the upper end of which is open. The partition 10 is 100 provided with a valve opening 26, which is preferably centrally disposed with respect to the bottom of the tubular member 25, and this opening 26 forms a means of establishing communication between the tubular 105 member 25 and the lower chamber 9 of the auxiliary receptacle. The reference character 27 designates a bracket, which is secured as at 28 to the under face of the partition 10, and said bracket forms a guiding means 110

for the rod 29. This rod 29 extends through the tubular member 25, and has an extension 30 adapted to slide in the tubular extension 21 of the housing 20 heretofore mentioned. 5 Mounted adjacent the upper end of this rod 29, is a valve member 31 and said valve member is adapted to engage the valve seat 22 to shut off the pipe or tube 23 and relieve the chamber 8 from the influence of the 10 vacuum produced in the heretofore described manner. Surrounding the opening 26 is a valve seat 33, and carried by the rod 29 is a valve member 34', which is adapted to seat on the valve seat 33 to close the opening 26, which establishes communication between the tubular member and the lower chamber 9 of the auxiliary receptacle 6.

The reference character 35 designates a float secured to the rod 29. The reference 20 character 40 designates a tube or pipe which is adapted to establish communication between the upper chamber 8 and the lower chamber 9 of the auxiliary receptacle, and said pipe or tube 40 is secured at one end 25 as at 41, to the partition 10 on its under side. The other end of this pipe 40 is provided with an elbow or similar fitting 42, the open end of which is formed with a valve seat 43 and is positioned beneath the 30 opening 26 in the partition 10.

Carried by the rod 29 is a valve 44, and said valve 44 is adapted to engage the valve seat 43 to close the open end of the pipe or tube 40. The reference character 50 designates the supply line for the charge-forming device and said pipe 50 extends upwardly 35 into the lower chamber 9 of the auxiliary receptacle 6, as indicated by the reference character 51, in order that sediment, water, or other material detrimental to the operation 40 of the charge-forming device may settle at the bottom of the chamber 9 and the fuel be drawn off at a level thereabove.

For the purpose of draining the deposits 45 in the lower chamber 9 of the auxiliary receptacle, a drain cock 51 is employed, and in order that the device may readily operate, the lower chamber 9 is adapted at all times to be in communication with the atmosphere 50 by means of the vent pipe 52.

The operation of the device is as follows: The main supply tank 5 carries the fuel in bulk, the auxiliary receptacle 6 merely serving at all times to have sufficient quantity of the fuel contained therein to insure a smooth 55 working of the charge-forming device. As the motor is started with the parts in the position shown in the drawings, a vacuum is created in the upper chamber 8 of the auxiliary receptacle 6. The production of this vacuum causes a flow of fuel from the main tank 5 into the chamber 8, through the medium of the pipe or tube 7. As the fuel continues to flow into the upper chamber 8, 60 it overflows through the open end of the

tubular member 25, and said tubular member likewise begins to fill. As this tubular member becomes approximately three-quarters full, the float 35 therein rises to close the valve 31 against the valve seat 22. With 70 the parts in this position, the vacuum through the pipe 23, which is produced by the engine in its operation, serves to aid in maintaining the valve 31 to its seat 22, thus shutting off the vacuum produced from the 75 chamber 8.

It will be noted that as the valve 31 engages the seat 22, the valve 44 is disengaged from the seat 43. This action opens the end of the pipe 40, and permits the fuel in the 80 chamber 8 to drain therethrough into the chamber 9. Simultaneously with the closing of the valve 31 and the opening of the valve 44, the valve member 34' is lifted from its seat 33 to provide a drain for the tubular member 25. With the valve 34' open, air is permitted to pass upwardly through the tubular member 25 to displace the fuel in the chamber 8. After the fuel in the chamber 8 has been completely displaced, the tubular member 25 is drained to permit of a lowering of the float to repeat the cycle of operation.

It will also be noted that the opening 26 in the partition 10 is considerably smaller 95 than the opening 43 in the pipe 40. In fact, the best results have been obtained by having this opening 26 about one-third the size of the opening 43. As the chamber 8 and the tubular member 25 become drained, the 100 valves 34' and 44 are closed by the falling of the float, and, at the same time, the valve 31 is opened.

The foregoing has described one cycle of operation of the apparatus and it is to be 105 understood that each time that the tubular member 25 and the chamber 8 are drained of their contents, the apparatus automatically operates to again establish communication between the chamber 8 and the manifold of the engine in order that the vacuum may again be produced in the chamber 8 to fill the same with fuel as heretofore described. The charge-forming device receives its fuel from the chamber 9 by means 110 of the pipe 50, which as heretofore stated, is connected therewith.

I claim:

1. In a vacuum feed system, vacuum producing means, a vacuum chamber, a float chamber, a float in said float chamber, a rod secured to the float in said float chamber, a valve at the lower end of said rod for controlling the discharge from the vacuum chamber to the fuel chamber, and a valve at 120 the upper end of said rod for checking the vacuum producing means, said float chamber serving as an overflow and vent for the vacuum chamber.
2. In a vacuum feed system, a fuel sup- 130

ply, a fuel chamber, a vacuum chamber, a vacuum producing means, a float chamber located in the vacuum chamber, a float mounted in the float chamber, and means 5 operated by the float in the float chamber for simultaneously checking the vacuum producing means and draining said vacuum chamber.

3. A vacuum feed fuel system, comprising 10 a fuel supply, a vacuum chamber, means for producing a vacuum in said chamber, a fuel chamber, means for establishing communication between the fuel chamber and the vacuum chamber, a valve controlling said 15 communicating means, a valve controlling the vacuum producing means, a float chamber located in the vacuum chamber, and a float movable in the float chamber and adapted upon its movement to simultaneously 20 operate the valve in the communicating means between the fuel chamber and the vacuum chamber and the valve of the vacuum producing means.

4. A fuel feed system comprising in combination with a vacuum producing means, a vacuum chamber, a fuel supply, means connecting the fuel supply with the vacuum chamber, a fuel chamber, means connecting the fuel chamber with the vacuum chamber, 25 a float chamber located in the vacuum chamber and adapted to receive the fuel therefrom, and means movable in the float chamber for simultaneously controlling the vacuum producing means and establishing communication 30 between the vacuum chamber and the fuel chamber.

5. In a vacuum fuel system, the combination with a vacuum producing means, of a fuel supply, a vacuum chamber, a fuel chamber, means for connecting the vacuum chamber with the fuel chamber, a float chamber in the vacuum chamber and in communication therewith and in communication with 35 the fuel chamber, a valve for controlling the connection between the vacuum chamber and the fuel chamber, a valve for controlling the connection between the float chamber and the fuel chamber, a valve for checking the vacuum producing means, and means for simultaneously operating said valves.

6. In a vacuum fuel system, the combination with a vacuum producing means, of a fuel supply, a vacuum chamber, a fuel chamber, means for connecting the vacuum chamber with the fuel chamber, a float chamber 45 in the vacuum chamber and in communication therewith and in communication with the fuel chamber, a valve for controlling the connection between the vacuum chamber and the fuel chamber, a valve for controlling the connection between the float chamber and the fuel chamber, a valve for controlling the connection between the float chamber and the fuel chamber, a valve for checking the vacuum producing means, and means 50 in the float chamber and movable by the rise of liquid therein, said movable means serving to simultaneously actuate said valves.

7. In a vacuum fuel system, a vacuum producing means, a valve for checking the action thereof, a fuel supply, a vacuum chamber, a fuel chamber, means connecting the fuel chamber with the vacuum chamber, means connecting the vacuum chamber with the fuel chamber, a float chamber mounted in the vacuum chamber, a valve for controlling the means connecting the vacuum chamber with the fuel chamber, a valve adapted to open or close communication between the float chamber and the fuel chamber, a valve for checking the action of the vacuum producing means, and a float for 65 simultaneously operating said valves, the valve of the float chamber serving first as a vent for the vacuum chamber and subsequently as a drain for the float chamber.

MORRIS PARNES.
